[57] CLAIM

The ornamental design for a vending machine or similar article, as shown and described.

DESCRIPTION

FIG. 1 is a front and right side perspective view of a vending machine or similar article showing my new design;

FIG. 2 is a left side elevational view thereof;

FIG. 3 is a right side elevational view thereof;

FIG. 4 is a top plan view thereof;
FIG. 5 is a front and right side perspective view of a modified form of the vending machine shown in FIG. 1; and

FIG. 6 is a top plan view thereof, the rear and bottom of the machine are substantially plain and unadorned and the right side of the machine shown in FIG. 5 which is not disclosed is the mirror image of the left side disclosed therein, the broken line showing of the indicia in FIGS. 1-3 and 5 is for illustrative purposes only and forms no part of the claimed design.

FIG. 1.FIG. 2.*FIG. 3.*FIG. 4.*FIG. 5.*FIG. 6.
